UNITED STATES PATENT OFFICE

WILFRED R. TOBIAS, OF LOS ANGELES, CALIFORNIA

ROOF

Application filed August 10, 1927. Serial No. 211,910.

My invention is a roof formed of slates, and the inventive feature is in the manner of attaching the slates to a roof, forming a double thick roof.

5 An object of my invention is the construction of a slate roof with slates arranged in double thicknesses, said slates overlapping at the upper ends so that nails secured in each slate will be only driven through one 55 slate into the frame of the roof.

In constructing my roof I utilize slates of different lengths, preferably of two different lengths considered from the ridge of the roof to the eave, and each row of slates is of double 15 thickness with the shorter slates underneath the longer slates, each slate being secured by a nail at its upper edge to the roof structure.

My invention is illustrated in the accompanying drawings in which:

20 Figure 1 is a perspective view of a roof constructed in accordance with my invention.

Fig. 2 is a section through the roof as if taken on the line 2—2 of Figure 1.

Fig. 3 is a plan of the roof partly broken 25 away.

Fig. 4 is a perspective view of two of the different length tiles.

Fig. 5 is a fragmentary sectional view of the lower merging edges of the upper and 30 lower layers of a row of slates.

In constructing my invention I utilize in each row of slates, a series of lower slates 11, each having nail holes 12 adjacent their upper edge and on top of these there is an upper row of slates 13 also having nail holes 14 at their upper ends. The longitudinal measurement of the slates 11, indicated by the numeral 15, is less than the longitudinal measurement of the slates 13, indicated by the numeral 16. That is, the upper slates are longer than the lower slates, but it is immaterial whether the slates have the same width indicated by the measurement 17.

45 A roof structure is indicated by the numeral 18, and the slates are arranged so that for instance, the lowest row 19 has the lower edge supported on a longitudinal strip 20, and the upper end of the lower slate 11 is secured by one or more nails 21, whereas the 50 upper end of the upper slate 13 is secured by

another nail or a set of nails 22. It will be noted that the nails 21 and 22 are spaced apart considered in relation to the roof structure from the ridge to the eaves, and therefore there is only one nail or one row of nails through each of the slates, and the nails do not have to pass through two slates.

From my construction it will be seen that the roof is of a simple type to make, and only requires that the slates be of different 60 lengths, and preferably of only two different lengths so that the upper slates of each row may overlap the lower slates, and that there will be no necessity of securing nails through two slates, that is, through an upper and a 65 lower slate.

Another characteristic of my invention is that the lower edge 23 of each tier of slates forms a line from one end of the roof to the other. Whereas this horizontal line described by the lower edge of each tier, is preferably substantially straight, it will be found upon closer inspection that the lower edge of each slate is rough and irregular, giving the appearance of having been broken instead of cut. Furthermore, this lower edge is more or less curved when viewed from the side of the slate, and instead of being disposed at right angles with the plane of the slate, it extends at an obtuse angle, so that it 70

slopes downward toward the eaves of the roof when the slate is in operative position. In assembling the slates, a more attractive roof is produced if care is exercised to so dispose each upper slate that its sloping lower 85 edge substantially merges into, and forms a continuation of the corresponding edge of the slate or slates therebelow. When so constructed, a casual observance of the roof, will not reveal that it is constructed of tiers, each 90 of which consists of two layers of slates, but the roof will appear to be made up of slates of double thickness. The roof thus composed of two layers of slates, will serve more 95 efficiently in preventing leakage there-through, than if the slates were of a single thickness, inasmuch as each line of separation between two slates, extending perpendicularly to the ridge line of the roof, will have 100 thereunder, substantially twice as many

thicknesses of slate, thus doubling the assurance that any water that leaks through the uppermost of these lines of separation, will be caught by the top surface of a slate thereunder, and discharged from the lower edge of that under slate, before this leakage has a chance to penetrate one of the corresponding lines of separation in the under tier.

Various changes may be made in the principles of my invention without departing from the spirit thereof, as set forth in the description, drawings and claim.

I claim:

In a roof construction, a covering composed of rows of slates, each row comprising an upper and a lower layer of slates, the lower edge of each slate being in obtuse angularity with the plane of the slate, and the lower edges of the slates of said upper and lower layers of each row, merging into each other to present a substantially continuous lower edge for said row of slates, and the slates of each upper layer being longer than and overlapping those of the associated lower layer, and fastening means extending through each slate, each fastening means engaging but one slate.

In testimony whereof I have signed my name to this specification.

30 W. R. TOBIAS.
